Inc., Indianapolis, Ind., a corporation of Del-
aware

Application March 23, 1935, Serial No. 12,595

1 Claim. (Cl. 201—73)

This invention relates to resistance devices and more particularly to variable resistors for electric current circuits.

An object of the invention is to produce an improved resistance element and an improved base structure therefor.

Other objects are to provide an improved resistance material and an improved binder therefor.

10 Further objects are to improve the resistor structure, the terminal and tap connections thereto, and the contacting elements therefor.

Still further objects are to improve the methods of making the resistor, including the base for the resistance unit, and to improve the method of applying the resistance surface thereto.

Other objects of the invention will be apparent from the following description and accompanying drawings taken in connection with the appended claim.

20 The invention may be embodied in a variable resistance device of the type commonly used in radio circuits and the like for volume control purposes and in general applications to control the amount of current flowing in a circuit. In one form, the device may comprise a ring or disc of insulating material upon the surface of which is an adherent coating of resistance material. A centrally pivoted arm may be provided, carrying 25 a rider or contactor adapted to travel along said resistance coating in contact therewith.

The invention contemplates improved methods of making the insulating base to provide a somewhat porous adherent surface for the resistance coating. It also contemplates a resistance coating of improved resistance material and an improved binder therefor whereby a uniform, highly adherent resistance surface is provided. The invention also contemplates improved terminal and tap arrangements and an improved sliding contacter.

40 The invention accordingly comprises the features of construction, combination of elements, arrangement of parts, and methods of manufacture referred to above or which will be further brought out and, exemplified in the disclosure hereinafter set forth, including the illustrations in the drawings, the scope of the invention being indicated in the appended claim.

45 For a fuller understanding of the nature and objects of the invention as well as for specific fulfillment thereof, reference should be had to the following detailed description taken in connection with the accompanying drawings, in which:

Figure 1 is a face view of the variable resistance device, with the cover therefor in section;

Figure 2 is a section on the line 2—2 of Figure 1;

Figure 3 is a back view of said device; 5

Figure 4 is a side view thereof with the cover removed;

Figure 5 is a detail view taken on the line 5—5 of Figure 1, showing the sliding contacter;

Figure 6 is a detail sectional view taken on the line 6—6 of Figure 1, to illustrate the terminal connection;

Figure 7 is a face view of a modified form of resistance unit;

Figure 8 is a section on the line 8—8 of Figure 7;

Figure 9 is a view of another modified form of resistance unit with parts broken away;

Figure 10 shows a tap connecting member for the unit shown in Figure 9; 20

Figure 11 is a perspective view of the resistance unit showing its structure in greater detail;

Figure 12 illustrates a method of making the insulating backing for said resistance unit;

Figure 13 is a section through the insulating 25 backing;

Figure 14 is a section through a modified form of backing; and

Figure 15 is a section through another modified form of backing. 30

Like reference characters indicate like parts in the several figures of the drawings.

While a preferred embodiment of the invention is described herein, it is contemplated that considerable variation may be made in the method 35 of procedure and the construction of parts without departing from the spirit of the invention.

Referring to the drawings, and particularly to Figures 1 to 4 the variable resistance device 20 comprises a base formed of two superimposed 40 discs 21 and 22 of insulation, such as fibre impregnated with a synthetic resin. Discs 21 and 22 each have suitable cut-out portions to accommodate other parts of the resistor structure. A metal cover or cap 19 is secured to the discs 21 45 and 22 by ears 19a and encloses the operating parts.

Superimposed upon disc 22 of the base is a ring 23 of insulating material, such as resin-impregnated fiber, having a coating 24 of resistance 50 material upon the outer face thereof, the coating 24 being left off a short sector of the insulating ring so that two ends to the resistance coating are provided.

Resistance surface 24 may be formed by sus- 55

pending a finely-divided resistance material, such as graphite or carbon, in a suitable liquid binder or carrier and painting or spraying the mixture onto the surface, after which heat may be applied to dry the binder or carrier. The binder in which the finely divided resistance material is suspended may be shellac, lacquer or other resins. For example, rosin may be used, it being preferably deposited by the volatilization of a suitable liquid carrier or solvent.

According to a modification other finely-divided conductive materials may be used in place of the carbon as the resistance material. Such a material may be finely divided metal, such as nichrome, iron, silver, metallic oxide, such as copper oxide, cadmium oxide, silver oxide or the like; metallic sulfide, such as copper, cadmium or silver sulfide, or the like. These materials provide superior resistance surfaces for some applications and may be used in suspension in liquid carriers as described for carbon. Likewise, the materials may be made of colloidal dimensions if desired to obtain a very smooth continuous surface.

Conductive terminal coatings 25 and 26 (see Figure 6) are applied over the ends of the resistance coating to provide for a good end connection. The terminal portions may be applied by spraying metal coatings onto the ends of the resistance coating with a metal spray gun, such as is used in the Schoop process, or by spraying or painting thereon a conductive paint. Where the surface is applied by a metal spray gun, the ring 23 may subsequently be placed in a press to embed the metal particles in the ring and produce a smooth conductive surface. A conductive paint may be made by suspending finely-divided silver oxide or silver sulfide, in a carrier or vehicle, such as gum lac or enameline "B" lacquer, bronzing oil or amyl acetate. After applying the paint to the surface, the unit may be heated to drive off the carrier and deposit the conductive compound in an adherent coating on the surface. A conductive paint comprising colloidal silver suspended in an oil may also be used.

Terminal bolts 27 and 28 pass through ring 23 and base disc 22 and are electrically connected to terminal coatings 25 and 26, respectively, by suitable conductive bushings. Terminal lugs 29 and 30 are secured by bolts 27 and 28, respectively, underneath disc 22 and project out beyond the base to provide for external circuit connections to the two ends of the resistance surface. Bolts 27 and 28 not only serve as terminals but likewise clamp the ring 23 to base disc 22. Bolt 28 also has a sector 31 of an insulating material clamped under its head to serve as a stop member for the contacter arm.

Discs 21 and 22 are clamped together at their centers by a metal bushing 32 which passes through these members and a metal spider 33 clamped against the back of disc 21 by bushing 32.

A metal contact ring 34 having an integral terminal lug 35 is mounted against the face of disc 22 within the resistance unit ring 23 and concentric therewith. Ring 34 is held in place by a rivet or eyelet 36 which clamps disc 24 and lug 35 together.

The variable contacter structure comprises a shaft 37 rotatable in bushing 32, a contact arm 38 secured to the end of shaft 37 on the face side of said resistance device, a sliding contacter 40 mounted on the end of said arm and adapted to

slide on resistance surface 24, and sliding contact fingers 39 integral with said arm and adapted to slide on contact ring 34. Shaft 37 is held against axial motion by clip washer 60 fitted in an annular groove in shaft 37 adjacent the rear end of bushing 32. Contact arm 38 is secured to the end of shaft 37 and insulated therefrom by a small piece of sheet insulation 41 the end of said shaft being upset to hold said piece 41 in place. Contact arm 38 and piece 41 are clamped together by a rivet pin 42. Pin 42 has a projecting portion 43 for operating a switch element which may be secured to the cover, if desired, so that the switch actuating lever is engaged by projection 43. Arm 38 and contact fingers 39 are 15 of spring construction and are held in tension by clip washer 60 so that the sliding contact portions are held in contact with their respective ring surfaces.

Sliding contacter 40 (see Figure 5) comprises 20 a section of a coil spring having a plurality of turns of uniform diameter each of which is in sliding contact with the resistance surface 24 whereby a novel and highly advantageous multiple contact is made between the arm 38 and the 25 surface 24.

It has been found that the most desirable contact surface for a sliding contacter is a smoothly rounded convex surface and preferably a plurality of these surfaces providing a number of 30 contacts over a small area of the resistor surface. Contacter 40 fulfills both of these requirements, providing a plurality of rounded contacting portions independently resiliently held against the resistor surface. Contacter 40 is fitted into a rectangular hole in the end of arm 38, the hole being slightly narrower than the diameter of the coil spring and of substantially the same length. Coil spring 40 is held in position by a thin sheet metal staple 44 fitted over the end of arm 38 with 40 one of its legs passing through the spring on top of the arm.

In operation, the terminal lugs 29, 30 and 35 are connected into an external circuit in any desired manner. By turning shaft 37 with a knob 45 or other control means sliding contacter 40 will slide on the resistance surface 24 in a circular path, the separate turns of spring contacter 40 each bearing against surface 24 and traveling in a direction parallel to their planes. Thus the 50 length of the resistance path, and consequently the magnitude of the resistance in series with terminal lugs 29 and 35 or 30 and 35 may be varied. Conductive coating 25 extends out a sufficient distance from terminal bolt 27 so that contacter 40 55 may ride up onto it as it approaches the terminal, thereby reducing the resistance to a negligible value. This enables the turning of arm 38 for a few degrees at the end of the stroke to allow for a switch to be operated by projection 43 on pin 60 42, if desired, without varying the resistance. The contact arm may be turned until it comes into direct contact with the bushing of screw 27 connected to lug 28, thereby reducing the 65 resistance to substantially zero. On turning the shaft in the opposite direction, however, the arm 38 is prevented from coming into contact with the terminal or terminal portion by insulating sector 31.

Figures 7 and 8 illustrate a modified form of resistance unit. This unit is similar to the one used in device 20 to the extent that it comprises ring 23 of insulation coated on one side with resistance surface 24 and conductive terminal 75

surface portions 25 and 26 but differs in that, in addition, a second resistance surface 46 is provided on the back of the ring 23 and similar conductive terminal portions, such as 45, and 5 provided therefor. This modified unit is adapted for use in a structure having two separately controlled sliding contacters, like 40, riding on opposite sides thereof. It is possible with this structure, to obtain certain desirable taper effects, 10 and the like since the resistance coatings may be connected in parallel in the circuit and only one need be altered at a time.

Figures 9 and 10 illustrate a means for obtaining a tap connection to the resistance unit. A 15 band conductive material 47 is applied to the surface of ring 23 over resistance surface 24 at any desired point between the ends of surface 24. Band 47 may be applied in the same manner as terminal surfaces 25 and 26, that is with metal 20 spray or paint. A metal lug 48 is then clamped to ring 23 over conductive surface 47 by projecting ears 49, integral with the lug.

Figure 11 is a perspective view of the resistance unit used in device 20 shown in greater detail. The unit comprises ring 23 of insulating material, said ring being formed of laminae 50 and 51 of two different kinds. The thickness is exaggerated in the drawings for purposes of illustration. Laminae 50 may be formed of a relatively impervious material, for example, a synthetic resin, such as glyptal-phthalic anhydride resin, a phenolic condensation product, such as "Bakelite"; or a fibre impregnated with one of these resins; a urea resin, such as "Beetleware"; 35 cellulosic products, such as cellulose acetate, Celuloid, and the like; and other types of insulating sheet material. Laminae 50 may also be formed of sheet mica built up into a laminated structure and bonded together with a suitable binder, such 40 as a resin, a soluble silicate or the like. The commercial laminated mica products "Micanite" and "Micalex" are suitable. Lamina 51 comprises a relatively more porous material made integral with the surface of lamina or laminae 50. Among 45 the materials suitable for lamina 51 may be included papers of different degrees of porosity such as tissue paper, blotting paper or dexter paper, newsprint, bond paper, and manila paper; parchments, linen and straw paper and the like. The 50 choice of material will depend upon the specific characteristics desired in the finished unit.

Resistance coating 24 and terminal surfaces 25 and 26 are applied to the porous surface of lamina 51 and since these are ordinarily applied as a 55 paint or spray they will adhere perfectly to the porous surface and provide an integral unit in which there is no tendency for the resistance surface to loosen or come off. This has a decided advantage over such units as have been previously used in which the surface has been prepared for receiving the resistance coating merely by 60 sanding or roughening the surface or by providing a matte finish.

One method of making the insulating backing

23 is illustrated in Figure 12. A plurality of sheets 52 of resin impregnated fiber, paper or cloth are laid in a pile and a sheet 51 of tissue paper is laid on top of the uppermost sheet and press members as shown are brought together to press the sheets 5 into intimate contact. At the same time heat or other curing agencies are applied to the assembled sheets cementing them together. Some of the resin material flows into the pores of tissue paper 51 cementing this sheet to the resin impregnated backings. The resin does not impregnate sheet 51 completely, however, but passes only part of the way through the sheet, as shown in Figure 13, leaving the upper surface porous and absorbent.

Upon completion of the curing operation and after removal from the press, the assembly will be found to be cemented together into a unitary piece. As shown in Figure 12, the original sheets are square as that is the most readily available 20 shape and ring 23 may be cut or stamped from the completed cemented piece. It is also possible, of course, to cut the sheets in the desired shape prior to molding. A similar procedure may be followed 25 for the laminated mica structure.

Figure 13 is a sectional elevation of the completed ring 23 made according to the present invention, before the application of the resistance surface.

Figure 14 shows a modified form of ring structure 23a in which two porous surfacing sheets 51 and 55 are used on opposite faces of the portion 50. This has a decided advantage in that the member is symmetrical and no warping will take place. Accordingly this construction of the ring 35 is preferred for most uses. Where ring 23a is used in place of ring 23 in device 20 only one of the layers 51 and 55 is coated with the resistance material. If it is used as illustrated in Figures 7 and 8 both layers are coated.

Figure 15 shows a modified ring structure formed of a portion 50a of a non-laminated molded plastic, such as cellulose acetate, molded casein products, "Beetleware" and the like, for example, having porous sheets 51 and 55 molded integral- 45 ly onto its two faces.

While the present invention, as to its objects and advantages, has been described herein as carried out in specific embodiments thereof, it is not desired to be limited thereby but it is intended 50 to cover the invention broadly within the spirit and scope of the appended claim.

What is claimed is:

The method of making a resistance unit which comprises forming a base of sheet synthetic resin 55 by superposing a plurality of sheets of material impregnated with said resin, a surface sheet containing no resin, compressing said sheets to form an integrally united sheet of material having a surface of low resin content, and thereafter applying a resistance film to said low resin content surface.

HAL F. FRUTH.
